United States Patent Office

Des. 188,423
Patented July 19, 1960

188,423

HAND GRIP EXERCISER

Terry J. Fox, Hunt Lane, North Salem, N.Y.

Filed June 13, 1958, Ser. No. 51,335

Term of patent 14 years

(Cl. D34—5)

FIG. 1.

FIG. 2.

Figure 1 is a top perspective view as seen from the front of a hand grip exerciser embodying my new design, and

Fig. 2 is a bottom perspective view thereof, as seen from the rear.

I claim:

The ornamental design for a hand grip exerciser, substantially as shown.
